ATTORNEY

UNITED STATES PATENT OFFICE.

ALEXANDER CHRISTIE, OF SEATTLE, WASHINGTON.

HASP-FASTENER.

1,240,316.

Specification of Letters Patent. Patented Sept. 18, 1917.

Application filed January 29, 1917. Serial No. 145,297.

To all whom it may concern:

Be it known that I, ALEXANDER CHRISTIE, citizen of the United States, residing at Seattle, in the county of King and State of Washington, have invented a certain new and useful Improvement in Hasp-Fasteners, of which the following is a specification.

My invention relates to hasp fasteners for doors, and the object of my invention is to provide a hasp fastener which shall be adapted to be associated with a single door and its door frame, or to be associated with a pair of doors disposed in a single door frame there to operate releasably and rigidly to lock said door or said doors in a closed position.

A further object of my invention is to provide a hasp fastener so constructed that it will be particularly adapted to be associated with a pair of doors that is employed to close the rear entrance to a covered delivery wagon, such as is employed by mercantile houses for delivery of merchandise, whereby said pair of doors may be releasably held in such tightly closed position as will effectively prevent a rattling or vibration of the doors of said pair irrespective of any wear of the parts of said hasp fastener.

I accomplish these objects by devices illustrated in the accompanying drawings wherein Figure 1 is a view in front elevation of a hasp fastener embodying my invention; Fig. 2 is a view in longitudinal section on broken line 2, 2 of Fig. 1, showing the same associated with a pair of doors in their closed positions;

Fig. 3 is a fragmentary view in front elevation of parts of the same, showing one part in vertical cross-section on broken line 3, 3 of Fig. 2;

Fig. 4 is a plan view of the same, in association with a pair of doors, showing relative operative positions of the parts thereof; and

Fig. 5 is a fragmentary plan view of the same showing a modified arrangement of its parts.

Referring to the drawings, throughout which like reference numerals designate like parts, 5 and 6 represent a pair of doors which may be hinged at their outer side edges and adapted to close as illustrated in Figs. 2 and 4, against any suitable stop, as a door frame or stud 7.

A spring-like bar 8 of suitable metal, as

spring steel, is slightly curved to dispose its two end portions normally in planes that are at a slight angle to each other, as shown in Figs. 2 and 4, one of said end portions being provided with holes 9, 10 and 11, as 60 indicated by dotted circular lines in Fig. 3, through which holes 9, 10 and 11 extend bolts, as bolts 13, whereby said spring-like bar 8 may be bolted to a door, as the door 5 in the manner shown in Fig. 2. 65

Secured to the bar 8, between the heads of two of the bolts 13 and 14 and its outer side surface, is the base of a catch 12, of the form shown in Fig. 2.

Bolted to the front side of the door 6, by 70 bolts 14, is a bracket 15 to which is hinged one end of a straight latch bar 16 that is adapted to engage its inner side surface, at a point near its hinged end, with the outwardly curved end portion of the bar 8 75 when it is actuated to swing to the position parallel with the front surfaces of the doors 5 and 6, as shown in Fig. 2, whereby said end portion of the bar 8 will be pressed toward the door 6 and whereby the spring-like 80 action of said bar will tend to press the latch bar 16 outwardly from its said parallel position adjacent to the doors 5 and 6.

Extending through the latch bar 16, near its free end, is a slotted hole 17 through 85 which the catch 12 may project outwardly when said latch bar 16 is pressed toward the door 5 to its position shown in Fig. 2; and the outwardly projecting portion of said catch 12 is provided with a hole 18 in which 90 the loop of a pad-lock may be disposed, if it be desired to lock the doors 5 and 6.

Fixed in the free end portion of the latch bar 16 is a rivet whose head 19 projects from the outer side surface of said latch bar 95 16 to form a detent, and between said rivet and the slotted hole 17 is a hole through which extends the shank 20 of locking member 21 that is provided with a knob 22 and two lugs 23 and 24 which extend radially 100 from said locking member 21.

The shank 20 of the locking member 21 is longer than the thickness of the latch bar 16 and its inner end is provided with a washer 25 that is fastened to said inner end 105 by a screw 26; thus the locking member 20 may be drawn outwardly for the distance limited by said washer 25 so that, when required, the locking member 20 may be rotated without causing the lugs 23 and 24 to 110

engage with the rivet head 19 thereby to obstruct the rotative movement of said locking member 20, as indicated in Fig. 4.

If, however, the locking member 20 is disposed with the inner side surface of the lugs 23 and 24 in contact with the adjacent surface of the latch bar 16 then the rivet head 19 will act as a detent to obstruct a movement of the lug 23 or the lug 24 in one direction.

The lug 23 is adapted to engage with the catching surface of the catch 12 in response to a clock-wise rotative movement of the locking member 20, while the lug 24 is adapted to engage with the catching surface of said catch 12 in response to a counter-clockwise rotative movement of said locking member 20. But, such rotative movements can take place only when the locking member 20 is drawn outwardly to the point where the washer 25 will engage with the inner side surface of the latch bar 16, and, therefore in the operation of disposing the parts, as shown in Fig. 3, to lock the doors 5 and 6 it is necessary, first, to close the door 6 and then to close the door 5, whereupon the latch bar 16 may be swingingly moved to force inwardly the curved end portion of the bar 8 until the catch 12 projects through the slotted hole 17 for such distance that one of the lugs 23 and 24 can be moved to its locking position under said catch 12 while the locking member 20 is drawn outwardly to its fullest extent, and when if said lugs as, for instance, the lug 23, is in its locking engagement with the catch 12 then the pressure against the bar 16 is discontinued whereupon the force of the bar 8 will press the bar 16 outwardly to the position shown in Fig. 2 so that the rivet head 19 will engage with the lug 24 to prevent further rotation of the locking member 20 until the latch bar 16 is again pressed inwardly.

To unlock the doors the bar 16 is first pressed inwardly to permit the locking member 20 to be drawn outwardly till it can be turned without being obstructed by the rivet head 19 whereupon the lug 23 may be disengaged from the catch 12 in an obvious manner to permit said latch bar 16 to swing outwardly from said doors 5 and 6.

While the doors 5 and 6 are locked the bar 8 exerts a constant pressure against the bar 16 thus to prevent any rattling of the doors and the parts of the hasp fastener.

55

In Fig. 5 I have shown spring-like bars 28, one end of which is fastened to the inner side of the latch bar 16 in a position to engage its other end portion with the outer surface of the door 5 when said latch bar 16 is in a position to lock the doors 5 and 6; said spring-like bar 28 thus taking the place of the bar 8 of Figs. 2, 3 and 4 to perform the same function by the same mode of operation.

65

If my hasp fastener is to be used in connection with a single door then the bracket 15 is fastened to the door frame of such single door in the same manner that it is fastened to the door 6 of Figs. 2 and 4.

70

Obviously, changes may be made in the forms, dimensions and arrangement of parts of my invention without departing from the spirit thereof.

75

What I claim is:

A hasp fastener comprising a latch bar provided with a hinge on one of its end portions to adapt it to be hinged to a door frame, and provided with two holes disposed to extend through its other end portion; a locking member provided with a cylindrical shank and a radially projecting locking lug, said shank being rotatably disposed within one of said holes and being adapted to be moved in endwise directions therein; a detent fixed on said latch bar and disposed to adapt it to engage with said locking lug in response to a rotative movement of said locking member when said locking lug is in engagement with the adjacent side surface of said latch bar; a catch adapted to project through the other of said holes to make locking engagement with said locking lug; and a spring associated with said latch bar in a position to adapt it to exert a pressure against said latch bar when said locking lug is in engagement with said catch.

In witness whereof, I hereunto subscribe my name this 17th day of January A. D., 1917.

ALEXANDER CHRISTIE.
